ELECTRIC SWITCH WITH MINIATURE
TOGGLE MECHANISM

George B. Benander and Luther M. Sheldon, Oaklawn, R.I., assignors to General Electric Company, a corporation of New York

Application November 29, 1957, Serial No. 699,614

6 Claims. (Cl. 200—67)

The present invention relates to electric toggle switches and particularly to such switches with a miniature toggle mechanism that will provide space for pressure-lock terminals of the type taught in the Benander Patent No. 2,705,785, which is assigned to the same assignee as is the present invention.

In the wiring device industry there is what is known as the interchangeable line of devices which are mounted in a single mounting strap. For instance, a single strap might support a single outlet, a toggle switch and a pilot light. Many other combinations of these three devices may also be used. In all cases the interchangeable devices are of minimum size so that the mounting strap carrying the three devices can be installed in a single electrical box with sufficient room for accommodating the many lead wires that would be attached to the devices.

In recent years pressure-lock terminals have been substituted for the standard screw terminals in many wiring devices. The present invention represents a miniaturization of the toggle mechanism of an electric toggle switch so that pressure-lock terminals can be accommodated within a switch housing for use in the interchangeable line.

The principal object of this invention is to provide an electric switch with a miniature toggle mechanism of narrow dimensions so that pressure-lock terminals may be combined within the switch housing.

A further object of this invention is to provide an electric switch with a simplified toggle mechanism whereby a coil spring is used to join the trigger and flapper of the switch.

The switch of the present invention has a hollow housing of insulating material with a manually-operable trigger pivotally mounted by means of trunnions on the opposite side walls of the housing. The lower end of the trigger has a downwardly-extending pin with a small slot formed in the bottom portion to receive the upper end of a movable flapper that is to be operated by the trigger. This flapper is of thin insulating material formed in the shape of a heart with an upper extension fitted into the slot of the trigger. A coil spring is slipped over the upper extension and is telescoped over the lower end of the trigger to form a flexible connection between the trigger and flapper. Side abutments are included on the lower pin of the trigger to serve as stop means that will hold the spring in compression and give this toggle mechanism a snap action. The bottom wall of the housing has a narrow concave track extending lengthwise of the housing so that the pointed bottom end of the flapper may be supported and guided therein. A pair of spring contact blades are arranged at one end of the housing to be on opposite sides of the track. The insulating flapper carries a bridging contact in the form of a rivet or eyelet that connects the spring contact blades when the flapper is forced between the blades as the trigger moves to one of its extreme positions.

Our invention will be better understood from the following description taken in connection with the ac-

2

companying drawings and its scope will be pointed out in the appended claims.

Figure 1 is a side elevational view of an electric toggle switch embodying our invention.

5 Figure 2 is an exploded view of the switch of Figure 1.

Figure 3 is a cross-sectional, elevational view through the longitudinal center of the switch showing the trigger in the Off position.

10 Figure 4 is a cross-sectional, elevational view similar to that of Figure 3 with the trigger shifted to the On position and showing in dotted lines the approximate position of the trigger before the flapper begins its flight into the closed circuit position.

15 Figure 5 is a plan view of the recessed base which forms the major portion of the switch housing for enclosing the toggle mechanism.

Figure 6 is a cross-sectional, elevational view of the switch housing of this invention taken on the line 6—6 20 of Figure 5 to show the manner of supporting the pressure-lock terminals.

25 Referring in detail to the drawing and in particular to the exploded view of Figure 2, the switch housing comprises a recessed base 10 that is generally rectangular in plan view. This base has side walls 11, end walls 12, bottom wall 13 and an open top wall 14. This top wall 14 is closed by a removable cover member 15 that fits snugly into the interior of the base and rests on the supporting posts 16 formed on the interior of the end walls

30 12. The cover plate 15 includes a raised collar 17 on its top surface. The collar encircles an opening 18 in the cover for receiving a manually-operable trigger 19 therethrough. The trigger 19 has a pair of trunnions 20 that rest on the partitions 21 formed on the interior

35 of the side walls 11 of the base. These trunnions 20 are confined in a pair of complementary notches 22 cut in the side of the cover plate 15 as is clearly seen in Figure 1. A metal mounting strap 25 is fastened over the cover and to the end walls 12 of the base to hold the switch

40 housing intact, as will be well understood by those skilled in this art.

The pressure-lock terminals will now be discussed to lay the groundwork for the thesis that there is very little space available in the switch housing for the toggle mechanism.

45 The space factor is a crucial one which emphasizes the importance of the miniature toggle mechanism disclosed and claimed herein. Looking first at the plan view of the base 10 of Figure 5, it should be understood that the base is divided into three chambers by a parallel

50 pair of longitudinally extending partitions 27. The chamber 28 between the partitions 27 is provided for accommodating the toggle mechanism which will be described in detail hereinafter. The remaining two chambers 29

55 and 30 extend along the sides of the base for accommodating the spring contact blades 31 and the pressure-lock terminals 32 as best seen in Figure 2. Two separate contact blades 31 are shown, and each blade has a contact tip 33 at one end and a terminal plate 34 at the opposite end. The end posts 16 of the base are T-shaped in

60 plan view, each post cooperating with a vertical slot 35 in the side walls 11 for receiving the terminal plates 34 of the contact blades.

Lead wires must be connected to the terminal plates 34 of the contact blades 31 before the switch can be used to 65 control an electric circuit. This is accomplished by means of the pressure-lock terminals 32 previously mentioned. Each such terminal has a spring locking tongue 36 that is seated on the bottom wall 13 of the base. The free end of the locking tongue 36 overlies a wire-receiving opening 37 in the base while the opposite end is formed at a re-entrant angle as at 38 and is braced against the projec-

tion 21 of the side wall 11. The re-entrant end 38 of the locking tongue then extends upwardly into a movable offset arm 39, terminating in an anchoring portion 40 that is held against the terminal plate 34 by means of a downwardly-extending lip 41 of the cover plate 15, as is best shown in Figure 6. This method of holding the pressure-lock terminal 32 in the switch housing does not form part of the present invention since it will be claimed in a copending application. Release openings 42 are formed in the bottom wall of the base so that a tool such as a screwdriver or large nail may be inserted to depress the locking tongue 36 and withdraw a lead wire.

With this background in mind, it will be understood that there is very little available space in the central chamber 28 of the switch base for installing a toggle mechanism. This difficulty has been overcome in a most unusual manner. First, the bottom wall of the base 13 in the area between the partitions 27 has been formed with a downwardly-extending well 45. In the bottom of this well there is a narrow concave track 46 that extends parallel to the partitions 27 for supporting and guiding an insulating flapper 47. This flapper 47 is best shown in Figure 2. It is stamped from thin sheet material with a lower portion 48 in the shape of a heart and an extension 49 extending upwardly therefrom. The pointed end 50 of the heart-shaped portion 48 is positioned in the narrow groove or track 46 of the base to move back and forth therein. Adjacent the pointed tip 50, a rivet or eyelet 51 is fastened to the flapper and extends therethrough. Thus, as is seen in Figure 4, when the flapper moves to the extreme right-hand position, the eyelet 51 serves as a bridging contact closing the circuit between the two spring contact blades 31.

The flapper 47 is flexibly connected to the trigger 19 in a very unusual manner to provide a snap acting toggle mechanism. The lower end of the trigger 19 has a downwardly-extending pin 55 carrying a pair of side abutments 56 that underlie the trunnions 20. The very tip of the pin 55 is spherical in shape and it is slotted as at 57 in Figure 2 for receiving and guiding the upper end of the extension 49 of the flapper. A coil spring 58 is used as the flexible connection between the flapper and trigger. The major portion of the spring 58 is telescoped over the extension 49 of the flapper. This spring is generally cylindrical in shape with an enlarged conical head 59 that fits snugly over the spherical end of the pin 55 and bears against the lower ends of the abutments 56 as is best shown in Figures 3 and 4. No additional pins, links or clip members are needed as in prior art toggle mechanisms of this general nature.

The operation of the toggle mechanism will now be discussed with particular relation to Figures 3 and 4. In Figure 3, the switch is in the Off position with both the trigger as well as the flapper in the extreme lefthand position. As the trigger is pivoted clockwise to the right about the fulcrums 20, the lower pin 55 of the trigger will move further down the extension 49 of the flapper, thereby compressing the spring 58 and slowly rotating the flapper in a counterclockwise direction about the end wall 12 of the base as a fulcrum. Gradually the central axis of the flapper will shift until it is aligned with the central axis of the trigger as is shown in dotted lines in Figure 4. As the trigger continues to move to the right, the spring 58 will be shifted off-center which immediately sets the toggle mechanism to operate as a mouse trap. Once the coil spring 58 is off-center, the trigger no longer compresses the spring but the reverse action take place, namely, the spring throws the trigger to the extreme right-hand position. In so doing, the spring also throws the flapper with a sudden start against the opposite end wall 12 of the base as shown in Figure 4. The spring contact blades 31 are spaced apart a distance slightly less than the thickness of the insulating flapper 47. The tips 33 of the blades are tapered outwardly so the flapper will spread the blades apart and provide a wiping action be-

tween the bridging contact 51 and the contact blades 31. Since the flapper 47 is of insulating material, there is an arc-snuffing effect provided by the flapper as the switch is shifted to the Off position. Exhaustive laboratory tests have proven that this switch has excellent electrical characteristics with a minimum of arcing on D.C. current tests. This results in long life expectancy for the switching operation due to the small amount of burning or eroding of the contacts.

Having described above our invention of a novel electric toggle switch, it will be readily apparent to those skilled in the art that we have devised a switch that has a minimum number of parts that are simple to manufacture and easy to assemble without the necessity for adjusting the contacts. The miniaturization of the toggle mechanism permits the use of pressure-lock terminals in the smallest line of toggle switches, namely, toggle switches for use in the interchangeable line of wiring devices where space is extremely limited. This invention, to our knowledge, represents the first A.C.-D.C. switch that has been furnished with pressure-lock terminals for the interchangeable line of wiring devices.

Modifications of this invention will occur to those skilled in this art and it is to be understood, therefore, that this invention is not limited to the particular embodiments disclosed but that it is intended to cover all modifications which are within the true spirit and scope of this invention.

What we claim as new and desire to secure by Letters Patent of the United States is:

1. An electric toggle switch comprising a hollow housing, a manually-operable trigger pivotally mounted in the housing about a transverse axis, the bottom wall of the housing having a narrow groove with a concave track extending lengthwise of the housing, and an upright heart-shaped flapper of thin insulating material supported edge-wise for sliding movement on the track and guided by the sides of the groove, the flapper having an upper extension that is received in a slot in the lower end of the trigger, and a coil spring fitted over the flapper extension and a portion of the lower end of the trigger to hold them together, the spring being under compression to establish a snap acting toggle mechanism, and a pair of spring contact blades arranged at one end of the housing on opposite sides of the track and representing the fixed contacts of the switch, the said insulating flapper carrying an electrically conducting member for bridging the two contact blades when the flapper is forced between them.

2. An electric toggle switch as recited in claim 1 where-in the lower end of the trigger has a downwardly-extending pin that is slotted at its distal end in a plane that includes the insulating flapper so that the upper extension of the flapper will be received therein, one or more abutments being formed on the outer surface of the pin for engaging the related end of the coil spring to serve as a stop means that is capable of exerting a compression force on the spring as the trigger is thrown from one extreme position to the other.

3. An electric toggle switch comprising a hollow housing, a manually-operable trigger pivotally mounted in the housing about a transverse axis, the bottom wall of the housing having a narrow groove extending lengthwise of the housing and provided with a concave floor, a thin insulating flapper of heart shape supported for sliding movement at its pointed end by the concave floor of the groove, and a spring member flexibly joining the insulating flapper to the lower end of the trigger to provide a snap acting toggle mechanism, and a pair of spring contact blades arranged at one end of the housing on opposite sides of the groove and representing the fixed contacts of the switch, the insulating flapper carrying an electrically conducting member that extends therethrough for bridging the two contact blades when the flapper is forced therebetween.

4. A toggle switch comprising a hollow housing having three compartments extending lengthwise of the housing, the two outside compartments each containing the terminal end of a spring contact blade and a pressure-lock terminal means including a spring locking tongue for attaching a bare conductor to the contact terminal, the said contact blades extending in a parallel manner into the central compartment to form the fixed contacts of the switch, and a snap acting toggle mechanism arranged in the central compartment and including an insulating flapper of thin plate construction with a pointed lower end that is supported in and guided by a narrow groove in the bottom wall of the housing, the flapper carrying a bridging contact that extends therethrough for engaging both of the contact blades when the flapper is forced therebetween.

5. A toggle switch as recited in claim 4 wherein the narrow groove in the bottom wall of the central compartment of the housing is a deep well with a longitudinally concave track on which the flapper is supported, the flapper being of heart shape with the pointed end bearing on the track for sliding movement.

6. A toggle switch as recited in claim 5 wherein the

5 flapper has an upper extension with a close-fitting coil spring thereover, the said toggle mechanism comprising the flapper, the coil spring and a pivoted trigger, the lower end of the trigger having a narrow slot receiving the upper end of the flapper extension, one end of the coil spring being enlarged and telescoped over the lower end of the trigger to establish a flexible connection between the flapper and trigger.
